CYLINDER CONSTRUCTION

**Kenneth A. Browne, Westwood, N. J., assignor to
Wright Aeronautical Corporation, a corporation
of New York**

Original application May 15, 1937, Serial No.
142,754. Divided and this application Septem-
ber 2, 1939, Serial No. 293,260.

14 Claims. (Cl. 123—193)

This invention relates to internal combustion engines, being particularly concerned with improvements in a cylinder construction and associated sleeve valve mechanism. Although the invention is particularly adapted for aircraft engines of the radial cylinder type, it is also suitable for various other types of engines. The present application is a division of application Serial No. 142,754, filed May 15, 1937.

A particular object of the invention is to provide a sleeve valve and sleeve driving organization in an engine which will permit of a minimization in the overall height of the cylinder assembly, and an associated object is to provide a sleeve valve and porting organization wherein the port openings will all be at the same level along the axis of the cylinder. An associated object is to provide a novel form of exhaust and intake manifold, permitting the use of a plurality of intake and exhaust ports. Still another object is to utilize a single set of ports in a valve sleeve having rotary and reciprocatory motions which are registerable sequentially with intake and exhaust ports in the cylinder walls. A further object is to provide a valve and manifold organization which will permit of a large cooling fin area upon the cylinder exterior, making the construction particularly suited for engines of the air-cooled type.

Another object is to organize the valve and porting arrangements in such a manner that the cylinder per se may be fabricated by simple machining operations, without recourse to complex milling operations and distorted masses of metal in the structure. This results also in the provision of a cylinder which is relatively free from unusual and unforeseen stresses.

A further object is to provide a novel form of sleeve valve operating mechanism, providing an orbit in the sleeve motion which is elliptical in shape, the minor axis of the indicated ellipse being parallel to the cylinder axis, whereby the overall height of the valve and cylinder assembly may be minimized.

Further objects will be apparent from a reading of the subjoined specification and claims, and from an examination of the accompanying drawings, in which similar numbers indicate similar parts, and in which:

Fig. 1 is an axial section through an internal combustion engine and a portion of the crankcase and associated structure, showing the provisions of the invention;

Fig. 2 is a horizontal section through part of the cylinder, showing the sleeve operating crank;

Fig. 3 is a vertical section through a part of the cylinder and sleeve actuating crank;

Fig. 4 is a developed diagrammatic view of the cylinder ports and sleeve ports, showing the orbit of movement of the sleeve and the various events of valve opening and closing with respect to crankshaft position;

Fig. 5 is a developed diagrammatic view of the valve orbit, showing the valve operation events;

Fig. 6 is a plan of the intake and exhaust manifolds for the cylinder; and

Fig. 7 is a side elevation of the upper portion of the cylinder with the manifolds installed.

In Fig. 1, a cylinder 10 is provided with concentric cooling fins 11, a port band 12 intermediate its height, and an attachment flange 13 seating upon a crankcase structure 14. A cylinder head 15, provided with cooling fins 16, is seated upon the top of the cylinder 10, and is fastened thereto by means of a union nut 17 overlapping a flange on the cylinder head and engaging screw threads 18 formed at the top of the cylinder 10. Said cylinder head has clearance with respect to the cylinder at 19, and is provided with junk rings 20 engaging the bore of a valve sleeve 21 extending below the bottom end of the cylinder. A boss 22 is formed at the lower end of the sleeve 21 and is provided with a ball socket 23 within which a ball 24 is movable, the ball having a bore slidably engaging a crankpin 25 of a sleeve operating crank 26, journaled at 27 in the crankcase. Said crank is driven by a gear 28 engaging a large annular gear 29 extending around a crankshaft 30, the ring gear being provided with spider journals 31, mounting gears 32, driven by a pinion 33, rotatable with the crankshaft 30. Rotatable with each gear 32 is a pinion 34 meshed with a fixed internal gear 35 fixed at 36 to the crankcase. Presuming a multi-cylinder engine of, say, nine cylinders, there will be a gear 28 and a shaft 26 for each cylinder, while a single annular gear 29 and driving mechanism therefor serves to drive all of the several gears 28, thus providing a single driving mechanism for all the valve gears.

It will be noted that the center of the ball socket 23 is radially inboard of the surface of the valve sleeve 21, which, to the best of applicant's knowledge, is a distinctly novel arrangement permitting of valve motions, as will be described later, much more favorable to compact engine design than has been accomplished heretofore. In prior constructions, it has been the conventional practice to have the driving boss for the valve sleeve radially outboard of the sleeve

itself, which in itself, unnecessarily lengthens the engine. By referring to Figs. 2 to 5, inclusive, it will be noted that the orbit of motion of the sleeve 21 is elliptical, the major axis of the ellipse, as shown in Fig. 5, being horizontal, and and the minor axis being vertical. This elliptical path is attained in the following manner: The vertical travel, or minor axis of the ellipse in Fig. 5, results from the eccentricity of the crankpin 25 as represented by the dimension A. The horizontal path of the sleeve is greater than the crankpin eccentricity A by virtue of the fact that the sleeve surface is radially more remote from the cylinder axis than is the center of the ball socket 23, the circumferential travel of the sleeve being represented by the dimension B. Expressing this in another way, the horizontal travel B of the sleeve bears the same relation to the dimension A as the sleeve radius bears to the distance from the center of the socket 24 to the cylinder axis.

By the elliptical sleeve orbit thus obtained, large valve openings are possible without increasing the overall height of the cylinder. The sleeve is provided with a circumferential plurality of ports 38 which coact with cylinder ports 39 and 40 connected respectively to intake and exhaust manifolds 41 and 42, there being a plurality of ports 39 and a plurality of ports 40 equal in number to the plurality of ports 38 in the sleeve 21. The action of the sleeve 21 is timed according to the diagrams of Figs. 4 and 5. In Fig. 4, the sleeve port 38 is indicated in various positions, in dotted lines, with respect to the intake and exhaust ports 39 and 40. The several valve combinations are marked in accordance with accepted terminology, as I. O. (intake opens); T. C. (top center); B. C. (bottom center); I. C. (intake closes); T. C. (top center); E. O. (exhaust opens); B. C. (bottom center); and E. C. (exhaust closes).

The intake manifold 41 consists of two symmetrical halves 44 and 45 bolted together at 46, each half having inwardly extending conduits 47 terminating in arcuate faces for fitting engagement with the valve band 12 on the cylinder, registering with the several ports 39. The exhaust manifold 42 is of forked form, being provided with conduits 49 terminating in pads in fitting engagement with the valve band 12 on the cylinder. Extensions 50 are fitted to the ends of the forked elements of the manifold 42, having pads for engagement with the valve band 12, such extensions being applied separately to permit of assembly of the manifold upon the cylinder.

Both manifolds are held tightly against the valve band 12 by means of a hoop 52 bearing upon projections 53 on each of the several valve port engaging conduits, this hoop having a turnbuckle 54 for tightening all the manifolds simultaneously. The turnbuckle is located diametrically opposite the terminals of the manifolds, and is supported away from the cylinder by a bridge element 55 bearing upon the valve band 12. In the arrangement shown, there are five exhaust ports 40 and six intake ports 39 in the cylinder, the segment of the cylinder opposite one of the exhaust ports 40 being covered by the bridge element 55, so that the compressive stress imposed by the hoop 52 is equally distributed throughout the periphery of the cylinder for minimizing warping stresses thereon.

Referring to Fig. 1, the space 19 between the cylinder 10 and cylinder head 15 is provided for vertical movement of the valve sleeve 21, where-

for the head itself is formed on its outer surface as a well, which, as previously indicated, is provided with cooling fins 16. In the installation of the engine, suitable cowling and baffling would be provided to direct cooling air into the well for effective heat removal therefrom.

The intake manifold 41, as shown in Fig. 1, is connected to an intake conduit 56 communicating with a pressure chamber 57 of a super-charger 58 driven by the engine crankshaft 30 in the conventional manner. Said engine crankshaft is carried on ball bearings 59 and 60 in the crankcase, the crankpin 61 having a conventional connecting rod system 62 upon which a piston 63 is borne to reciprocate in the cylinder 10, bearing upon the bore of the sleeve 21.

While I have described my invention in detail in its present preferred embodiment, it will be obvious to those skilled in the art, after understanding my invention, that various changes and modifications may be made therein without departing from the spirit or scope thereof. I aim in the appended claims to cover all such modifications and changes.

I claim as my invention:

1. In a sleeve valve engine comprising a cylinder having a plurality of circumferentially disposed ports therearound, a continuous circumferential seat around said cylinder and embracing the several ports, intake and exhaust manifolds each embracing more than half of the cylinder circumference and having conduits registering with respective ports, the conduit ends engaging said seat, and a hoop embracing said conduits for holding same against said seat.

2. In a sleeve valve engine comprising a cylinder having a plurality of circumferentially disposed ports therearound, a continuous circumferential seat around said cylinder and embracing the several ports, intake and exhaust manifolds each embracing more than half of the cylinder circumference and having conduits registering with respective ports, the conduit ends engaging said seat, a hoop embracing said conduits for holding same against said seat, and means for tensioning said hoop.

3. In a sleeve valve engine, a cylinder having a plurality of intake ports and a plurality of exhaust ports alternately arranged around the cylinder, the several ports all being at substantially the same distance from the end of the cylinder, a cylinder embracing intake manifold having conduits registering with respective intake ports, a cylinder embracing exhaust manifold having conduits registering with respective exhaust ports, each conduit having an abutment spaced from the cylinder, and a band bearing on respective abutments and embracing the conduits and cylinder.

4. In a sleeve valve engine, a cylinder having a plurality of intake ports and a plurality of exhaust ports alternately arranged around the cylinder, the several ports all being at substantially the same distance from the end of the cylinder, a cylinder embracing intake manifold having conduits registering with respective intake ports, a cylinder embracing exhaust manifold having conduits registering with respective exhaust ports, and unitary means for holding both said manifolds in assembled relation on said cylinder.

5. In a sleeve valve engine, a cylinder having a plurality of intake ports and a plurality of exhaust ports alternately arranged around the cylinder, the several ports all being at substan-

tially the same distance from the end of the cylinder, a cylinder embracing intake manifold having conduits registering with respective intake ports, a cylinder embracing exhaust manifold having conduits registering with respective exhaust ports, and means embracing both said manifolds for holding them in assembled relation on said cylinder.

6. In a sleeve valve engine cylinder comprising a plurality of substantially coplanar ports arranged around the cylinder, a conduit seating upon the cylinder adjacent each port, each conduit having an abutment, the several abutments being coplanar and spaced substantially the same distance outwardly from the cylinder wall, and a unitary member embracing the several conduits and engaging the abutments to secure the conduits against the cylinder.

7. In a sleeve valve engine cylinder comprising an annular port belt having ports therethrough, conduits for inlet and exhaust manifolds seating on the belt at respective ports and comprising elbows curved upwardly for one manifold and downwardly for the other manifold respectively from the plane of the port belt, a shelf on each conduit substantially on the central plane of the port belt annulus, and a tensionable wrapping member embracing the several conduits and resting upon respective shelves thereof.

8. In a sleeve valve engine cylinder comprising an annular port belt having ports therethrough, conduits for inlet and exhaust manifolds seating on the belt at respective ports and comprising elbows curved upwardly for one manifold and downwardly for the other manifold respectively from the plane of the port belt, a shelf on each conduit substantially on the central plane of the port belt annulus, a tensionable wrapping member embracing the several conduits and resting upon respective shelves thereof, and a manifold embracing the cylinder with which said conduits communicate.

9. In a sleeve valve engine cylinder comprising an annular port belt having ports therethrough, conduits for inlet and exhaust manifolds seating on the belt at respective ports and comprising elbows curved upwardly for one manifold and downwardly for the other manifold respectively from the plane of the port belt, a shelf on each conduit substantially on the central plane of the port belt annulus, a tensionable wrapping member embracing the several conduits and resting upon respective shelves thereof, said conduit elbows being alternately up-

wardly and downwardly facing, a manifold around the cylinder below the port belt with which said downwardly facing conduit elbows communicate, and a manifold around the cylinder above the port belt with which said upwardly facing conduit elbows communicate.

10. In a sleeve valve engine cylinder comprising an annular port belt having ports therethrough, the belt comprising a seat, a plurality of conduits each having an arcuate face engaging the belt at one of said ports, manifolds joining certain of the conduits, and unitary means engaging the several conduits exteriorly of the belt and urging the conduits against the belt with substantially equal pressure on each.

11. In a cylinder member having a plurality of substantially coplanar ports spaced thereabout, the member surface adjacent the ports comprising a seat, a conduit having an inner face engaging the seat at each port, the several conduits together embracing substantially more than half of the cylinder circumference and means wrapped around the several conduits and bearing thereon for holding the conduits in contact with the seat.

12. In an engine cylinder having a plurality of ports exposed to the outside of the cylinder, a gas conduit for each port seated against the outside of the cylinder and covering its port, said conduits together embracing substantially more than half of the cylinder circumference and unitary means embracing the cylinder and engaging the conduits to hold the latter against the cylinder.

13. In an engine cylinder having a plurality of ports spaced around and exposed to the outside of the cylinder, gas conduits seated against the outside of the cylinder and covering each port and together embracing substantially more than half of the cylinder circumference, unitary means embracing the cylinder and engaging the conduits to hold the latter against the cylinder, and a manifold secured to and communicating with said conduits.

14. In an engine cylinder having a plurality of ports exposed to the outside of the cylinder and comprising an annular cylinder surface embracing said ports, a plurality of conduits each having an end face complementary to said annular surface and overlying one port, and a band embracing the cylinder and conduits and in contact with each of the latter for holding the conduits in cylinder contact.

KENNETH A. BROWNE.
